UNITED STATES PATENT OFFICE.

JOHN W. WATKINSON, OF CHARLEROI, PENNSYLVANIA.

BUILDING BLOCK.

1,414,240.

Specification of Letters Patent. Patented Apr. 25, 1922.

Application filed January 7, 1921. Serial No. 435,638.

To all whom it may concern:

Be it known that I, JOHN W. WATKINSON, a citizen of the United States, residing at Charleroi, in the county of Washington and State of Pennsylvania, have invented certain new and useful Improvements in Building Blocks; and I do hereby declare the following to be a full, clear, and exact description of the invention, such as will enable others skilled in the art to which it appertains to make and use the same.

This invention relates to certain new and useful improvements in building blocks and has for its primary object the provision of a non-slipping building block which will be of simple construction, and operation and by means of which walls may be readily constructed in such a manner that the blocks will be prevented from slipping with respect to one another, thereby securely holding the walls in proper position.

The invention has for another object the provision of an improved form of building blocks including a corner block and a side wall block from which walls may be built at right angles to one another and connected at their meeting edges and the adjacent blocks of the walls securely locked with one another.

The invention has for another object the provision of an improved form of building blocks which will be inexpensive to manufacture, which will be adapted for various purposes such as constructing walls of a building and connecting the walls securely at the corners of the building by proper arrangement of the blocks and overlapping thereof.

The invention has for a still further object the provision of an improved form of building block of the character stated in which the blocks will be provided with interlocking grooves and ribs or tongues and the corner blocks also being provided with a transverse partition which will limit sliding movement of the side wall blocks thereon so as to be sure of proper arrangement of the blocks with respect to one another.

With the foregoing and other objects in view as will appear as the description proceeds, the invention consists in the novel construction, combination and arrangement of cooperating elements as hereinafter more specifically set forth, pointed out in the appended claims, and shown in the accompany-

ing drawings forming a part of the present application, and in which:

Figure 1 is a plan view of the interlocked corner portion of two walls at right angles to one another and constructed of the improved building blocks.

Figure 2 is a perspective view of the wall structure as shown in Figure 1, with an additional layer of blocks in position.

Figure 3 is a vertical section on the plane 65 of line 3—3 of Figure 1, looking in the direction indicated by the arrows.

Figure 4 is a view similar to Figure 3, taken on the plane of line 4—4 of Figure 1, looking in the direction indicated by the 70 arrows.

Figure 5 is a detail view of one of the corner blocks, removed.

Figure 6 is a detail view of one of the side wall blocks, removed, showing the lower face 75 thereof.

Referring more in detail to the drawings, in which similar reference characters designate corresponding parts throughout the several views, 1 indicates in general the corner block which is of rectangular form in elevation and plan as well as in end elevation, the block being preferably of a length equal to about twice the width or elevation thereof. The corner block 1 is open at its 85 upper and lower faces and is also provided with a transverse vertical partition 2 slightly nearer one end. The opposite end carries a depending central tongue 3 on its lower face while a corresponding recess or groove 4 is 90 formed centrally in the upper face of the last mentioned end which end may be designated by the numeral 5.

In connection with the corner block just described, I propose to employ side wall 95 blocks 6 which are also hollow and have open opposite ends, each side wall block 6 being provided upon its lower face with a longitudinal central rib 7 while a correspondingly depressed portion or groove 8 is formed 100 in its upper or central face.

The blocks 1 and 6 may be formed of plastic material or any other suitable material and may be of any convenient or appropriate sizes. It is also to be understood 105 that the block 6 is of elongated rectangular form and corresponds in size to the corner block 1.

By the proper use of the two blocks above described, walls and the like may be readily 110

constructed and the blocks of each layer and of each wall securely locked together and held against slipping or other independent movement of one another.

5 In building the structure from the blocks forming the subject matter of this invention, it is advisable to first provide a base of concrete or the like for each wall forming a part of the proposed structure. The blocks to be 10 employed for the lower layer of each wall are then placed in position, as will be understood by referring to the drawings, one corner block being employed for the block at the end of one of the walls where the two 15 walls are positioned at right angles to one another to be connected together. The second layer is then formed by placing the blocks for the second layer of each wall in overlapping relation with respect to the 20 blocks of the first layer or lowermost layer of the wall. In the case of the second layer of blocks, the corner block is employed for the other wall and the smooth end placed transversely across the smooth or outer end 25 of the corner block in the remaining wall of the first layer. The transverse partition 2 not only serves to strengthen the corner block 1 but also serves as a stop to be engaged by the end of the rib 7 on the side 30 block extended over the inner end of the corner block and as will also be readily understood by referring to the drawings. By reversing the corner blocks for each layer of the walls at right angles to one another, as 35 just described, the side wall blocks of each layer will be offset or overlapped with respect to the side wall blocks of the layers immediately above and below the same, thereby properly breaking the joint between the 40 blocks of the various layers of the wall structure.

It is to be understood that while the pre-

ferred embodiment of the invention has been shown and described, minor changes in the details of construction and arrangement of parts may be resorted to within the scope of what is claimed without departing from the spirit of the invention. 45

What is claimed is:—

1. In a wall structure, a corner block having a groove extended inwardly from an end wall thereof, stop means on said block at a distance from said wall, in combination with a block for partial disposition across said corner block having a rib to enter said groove and to abut said stop means. 50

2. In a wall structure, a corner block having a groove extended inwardly from an end wall thereof, stop means on said block at a distance from said wall, in combination with a block for partial disposition across said corner block having a rib to enter said groove and to abut said stop means, said corner block having a tongue depending therefrom adjacent the said end wall at the opposite side thereof to said groove, and a block beneath said corner block having a groove to receive said tongue. 60

3. In a wall structure, a corner block having an end wall provided with a groove and a tongue at opposite sides thereof, a partition wall in said block at a distance from said recess, in combination with a block for partial disposition across said corner block having a rib to enter said groove and to abut said partition member, and a block for partial disposition across said corner block having a groove into which said tongue extends. 70

In testimony whereof I affix my signature in presence of two witnesses.

JOHN W. WATKINSON
